UNITED STATES PATENT OFFICE.

GARTH G. GILPIN, OF RIVERSIDE, ILLINOIS, ASSIGNOR TO WALTER P. MURPHY, OF NEW YORK, N. Y.

DOUBLE-DOOR CONSTRUCTION FOR RAILWAY CARS.

Application filed May 29, 1920. Serial No. 385,102.

To all whom it may concern:

Be it known that I, GARTH G. GILPIN, a citizen of the United States, residing at Riverside, in the county of Cook and State of Illinois, have invented certain new and useful Improvements in Double-Door Constructions for Railway Cars, of which the following is a specification.

My invention relates to a side door construction for railway cars of the box car type, and the principal object of the invention is to provide certain improvements in double door constructions employed on box cars used for carrying automobiles or other large articles of freight. Automobile cars are frequently built with side door openings wider than those of the ordinary box car. These openings are closed, in such case, with a pair of doors which slide to and from each other, one of standard width and the other narrower as a general rule. The latter, when in closed position, is fastened firmly to the sill plate and header of the door frame and is opened only when the car is used for carrying automobiles or other bulky pieces of freight, the other door alone being opened when the car is loaded with small articles or with grain.

One of the specific objects of the invention is to provide certain arrangements for rigidly anchoring the small or auxiliary door (it may, of course, be the same width as the other) to the door frame, which arrangements do not involve the use of a heavy post or jamb member at the meeting edges of the door characteristic of most double automobile car door constructions. The post or jamb, besides being cumbersome and obstructing the doorway to a greater or less extent, adds so much weight to the auxiliary door, if, as in certain constructions, the post is fastened to the door or engaged to slide with it, that the door is likely to be injured or to cause breakage of or injury to the fittings with which it comes into contact when it is moved back and forth across the doorway.

A further object is to provide means associated either with one of the doors, with the auxiliary door for example, or with the door frame, for holding temporarily an upright timber or "coopering strip" for supporting the grain doors used when the car is loaded with grain or other bulk freight. Grain doors are made of a standard size to corre-

spond with the width of the ordinary box car door. In loading automobile cars having the wider door openings two grain doors are often used on a side. Some support is necessary for these grain doors at the middle of the door opening or at the meeting line of the doors.

In general, my invention seeks to provide a double door construction for freight cars which, while having the requisite strength and rigidity, will be simpler in structure, lighter and more economical to fabricate and install than the double door constructions heretofore used on railway box cars.

The invention is shown, in certain preferred embodiments, in the accompanying drawings wherein—

Fig. 1 is a fragmentary side elevation of a railway box car provided with the double door construction of my invention.

Fig. 2 is a sectional plan view, on a larger scale, taken on line 2—2 of Fig. 1.

Fig. 3 is a fragmentary view, in elevation of the structure taken from the inside of the car.

Figs. 4 and 5 are views, in perspective, of the stop and retaining members, one on the upper forward corner of the auxiliary door and the other on the header, for holding the door in its closed position.

Fig. 6 is a fragmentary view, in elevation, of the auxiliary door looking toward the forward edge of the same, the adjacent parts of the car body being shown in section.

Figs. 7 and 8 are perspective views of the stop and retaining members for the lower portion of the auxiliary door.

Fig. 9 is a horizontal sectional view on line 9—9 of Fig. 6, looking upwardly.

Fig. 10 is a view, similar to Fig. 6, showing a modified construction.

Figs. 11 and 12 are horizontal sectional views taken on lines 11—11 and 12—12 respectively, looking in the direction indicated by the arrows in each case.

Fig. 13 is a fragmentary view, in perspective, illustrating the intermediate guide for the locking element shown in Figs. 10, 11 and 12.

Fig. 14 is a sectional view on line 14—14 of Fig. 10.

Figs. 15 and 16 are perspective views of the coengaging stop and retaining members for the upper part of the door shown in the preceding five figures.

Fig. 17 is a view similar to Figs. 6 and 10 illustrating another modification, and Figs. 18 and 19 are sectional views taken on lines 18-18 and 19-19 respectively of Fig. 17, 5 looking in the direction of the arrows, in each case.

Like characters of reference designate like parts in the several figures of the drawings.

Referring first to Figs. 1 to 9 inclusive, 10 designates the side sheathing of a box car having a door opening 26. 27 are the door posts at opposite sides of the door opening. 28 represents one of the side sills of the car, 29 the side plate and 30 the header strip. 15 The main door is shown at 31 and the auxiliary door at 32. Both doors are shown as supported on brackets 33 provided with rollers 34, the lower edges of the doors being provided with Z-bar strips 35 to engage the 20 rollers 34. The upper edges of the doors are provided with outwardly opening channel members 36, the upper flanges of which project into the inwardly opening channeled portion of a guide strip 37 secured by bolts 25 38 to the side of the car. My invention is not concerned with these arrangements for supporting and guiding the doors. The rear edges of the doors are provided with angle bar weather strips 39 adapted to engage 30 angle bars 40 secured to the door posts 27. Secured to the forward edge of the main door 31 is a Z-bar 41. Extending around a forward edge of the auxiliary door 32 is a channel shaped strengthening and rigidifying member 42, the inner web 43 of which is offset at 44 to provide a recess to receive the forwardly projecting web 45 of the Z-bar 41. This arrangement makes the connection between the doors waterproof. The channel-shaped member gives great strength and 40 rigidity to the auxiliary door. The stop and retaining members employed for anchoring the forward edge of the auxiliary door to the door frame are attached to the channel-shaped reinforcing member 42 as will be hereinafter described. This construction makes it possible to omit the post or jamb members which in previous constructions have been either fastened to or interlocked 45 with the forward edge of the small door. A wooden timber fixed to or engaged with the forward edge of the door in order to be strong enough to give the necessary rigidity to the meeting edges of the doors and of 50 sufficient width to form a support for the grain doors, when such are used, overweights the small door so that when the door is thrown forward or back on its rollers the shock is likely to injure the door or its fittings.

In the construction shown in Figs. 1 to 9 inclusive, the small door is provided with stop and retaining members at the top and bottom of its forward edge which are 55 adapted to engage with a pair of stop and

retaining members on the door frame. 46 (Fig. 4) is the stop and retaining member at the top of the door. It is formed with an upstanding vertical oblique or wedging lip 47 adapted to engage a depending oblique lip 48 on the cooperating member 49 which is secured to the under side of the header 30. Member 49 has a web 50 which provides a stop for member 46 on the door. The latter is secured directly to the channeled reinforcing strip 42 which embraces the forward edge of the auxiliary door. At the lower forward corner of the door is a stop and retaining member 51 having a depending vertical, oblique lip 52 adapted to bear against the wedging surface 53 provided by a block 54 forming part of the stop and retaining member 55 secured to the flooring 56 of the car, preferably with the interposition of a sill plate 57. The member 51 is formed with a socket portion 58 in which is slidably arranged a bolt 59, the upper end of which has a horizontally projecting portion 60 to provide a handle. The lower end of the bolt is beveled, as indicated at 61 (Fig. 3) to engage a cam surface 62 formed on the top of block 54. When the door is moved to its closing position the lower locking bolt 59 rides up over cam surface 62 and drops down on the far side of the block. At the same time lip 52 engages surface 53 and lip 47 engages the surface 48. To hold the bolt 59 from dragging on the floor a U-shaped slot 63 is cut in the rear face 64 of socket 58 and the metal within the slot is bent inwardly to form a lip 65 projecting into a slot 66 formed in the bolt 59. The member 51 is formed with a pocket 67 for the lower end of a cooperating strip, shown in dotted lines at 68 in Fig. 6, the upper end of the strip seating in a pocket 69 formed in member 46. The use of the cooperating strip is only temporary at such time as the car may be loaded with grain. It provides a means intermediate the sides of the door opening for supporting the 100 grain door or grain doors which may be nailed thereto if necessary. Preferably the pockets are of a proper size to hold a two-by-four timber, timbers of this size being kept on hand at the elevators where the car 105 receives its grain cargo. The cooperating strip forms no part of the door construction and will be used only in case of transportation of bulk freight requiring supplemental means for preventing leakage at the door 110 opening.

The modified construction shown in Figs. 10 to 16 inclusive, provides for a locking element which locks the door at the top as well as at the bottom. This necessitates certain changes in the upper stop and retaining members but in other respects the construction is substantially that shown in the preceding figures. The locking bolt 70 passes through a socket formed in the member 71 115

on the door and engages a cam surface on the member 72 which is fixed to the sill plate. The upper end of the locking bolt passes through a socket 73 formed on a stop 5 and retaining member 74 (Fig. 16) which is secured to the upper forward corner of the door and is formed with an upstanding oblique lip 75 adapted to bear against a depending, oblique web 76 on the member 77 10 (Fig. 15) which is secured to the header of the door frame. The upper end of the locking bolt is bent over at right angles, as shown at 78, and is disposed so as to engage and ride over a cam surface 79 on member 77. The length and weight of the locking bolt make it desirable, although it is not absolutely essential, that it be lifted from the top as well as the bottom. The projecting end 78 after riding over cam 79 15 drops back of the web 80 of member 77 so that the upper two stop and retaining members are locked as well as the lower two. The locking bolt preferably passes through one or more guide castings 81 (Fig. 13) 20 secured to the door, one of such castings being shown in the drawings. Above this guide the locking bolt is provided with a rivet 82, the heads of which form stops to limit the downward movement of the bolt 25 30 so as to prevent it from dragging on the floor when the door is moved back and forth.

The modified construction shown in Figs. 17, 18 and 19 involves but a single change 35 over the construction shown in Figs. 10 to 16 inclusive. In Figs. 17, 18 and 19 the pockets for the coopering strip 68 instead of being formed on the stop and retaining members attached to the door are formed on 40 the members which are fixed to the door frame. 83 designates the pocket on the member 84 secured to the car floor. 85 designates the corresponding pocket on the member 86 secured to the header of the door frame. The other parts of the door construction are given the same reference numerals as are used to designate the corresponding parts shown in the previous figures.

50 While I have described my invention in certain preferred embodiments, it will be understood that changes in details of construction could be made without departure from the principles of the invention. 55 Therefore, I wish it to be understood that the invention is not to be considered as limited to the specific arrangements and constructions shown and described except so far as certain of the claims hereto appended are expressly so limited.

I claim:

1. The combination with a railway car 60 having a door opening, of a pair of doors to close said opening, and pockets secured to the inner face of one of the doors near

its upper and lower edges, respectively, adapted to receive and removably support a coopering strip, for the purpose described.

2. The combination with a railway car 70 having a door opening and a pair of doors to close said opening, of means on one of said doors adapted to receive and support a bodily removable upright coopering strip.

3. The combination with a railway car 75 having a door opening and a pair of doors movably attached to the car to close said opening, of two pairs of cooperating stop and retaining members, one pair on one of the doors and the other on the car body, 80 one of said pairs of members being recessed to provide seats for the ends of a coopering strip.

4. The combination with a railway car 85 having a door opening and a pair of doors to close said opening, of two pairs of cooperating stop and retaining members for limiting the closing movement of said doors and retaining them in their closed position, one pair on one of the doors and the other 90 on the car body, the members on the door being recessed to provide seats for the ends of a coopering strip.

5. The combination with a railway car 95 having a door opening and a pair of doors to close said opening, of stop and retaining members separately secured immediately to the inner face of one of said doors at its forward edge, and stop and retaining members on the car at the top and bottom of the 100 door opening, with which the members on the door engage.

6. The combination with a railway car 105 having a door opening and a pair of doors to close said opening, of stop and retaining members separately secured to the forward edge of one of the doors, stop and retaining members on the car body at the top and bottom of the door opening with which the members on the door cooperate, a longitudinally movable locking element carried by one of the members on the door, and a retracting cam for said locking element on the cooperating member of the car.

7. The combination with a railway car 115 having a door opening and a pair of doors to close said opening, of stop and retaining members at the forward edge of one of the doors, stop and retaining members on the car body at the top and bottom of the door opening with which the members on the door cooperate, a longitudinally movable locking element carried by the members on the door and having locking engagements with the other pair of members, one of the latter being formed with a retracting cam for said locking element whereby the locking element is automatically moved into locking position when said door is closed.

8. The combination with a railway car 120

having a door opening and a pair of doors to close said opening, of stop and retaining members at the forward edge of one of the doors, stop and retaining members on the 5 car body at the top and bottom of the door opening with which the members on the door cooperate, a longitudinally movable locking element carried by the members on the door and having locking engagements with the 10 other pair of members, the latter members being formed with retracting cams engageable by said locking element whereby the locking element is automatically moved into locking position when said door is closed. 15 9. The combination with a railway car having a door opening and a pair of doors to close said opening, of stop and retaining members at the forward edge of one of the doors, stop and retaining members on the 20 car body at the top and bottom of the door opening with which the members on the door cooperate, a longitudinally movable locking element carried by the members on the door and having locking engagement with the 25 other pair of members, one of the latter being formed with a retracting cam for said locking element whereby the locking element is automatically moved into locking position when said door is closed, and means 30 for limiting the downward movement of the locking element to hold the same above the floor level.

10. The combination with a railway car having a door opening and a pair of sliding 35 outside doors to close the same, of a pair of stop and retaining members separately secured to the top and bottom of the forward edge of one of said doors, a pair of stop and retaining members on the car within the 40 door opening, coengaging vertical, oblique, guiding surfaces on said members, a locking bolt socket in one of the members on the door and a cam surface on the cooperating fixed member adapted to automatically effect 45 the movement of the locking element to its locking position.

11. The combination with a railway car having a door opening and a pair of sliding outside doors to close the same, of a pair of 50 stop and retaining members at the top and bottom on the forward edge of one of said doors, a pair of stop and retaining members on the car within the door opening, coengaging vertical, oblique guiding surfaces on 55 said members, locking bolt sockets on the members upon the door, and a locking bolt passing through said sockets and adapted to engage the members on the car, one of the members on the car being formed with a cam over which said bolt rides when the door is closed. 60

12. The combination with a railway car having a door opening and a pair of sliding outside doors to close the same, of a pair 65 of stop and retaining members at the top

and bottom on the forward edge of one of said doors, a pair of stop and retaining members on the car within the door opening, coengaging vertical, oblique guiding surfaces on said members, locking bolt sockets on the members upon the door, and a locking bolt passing through said sockets and adapted to engage the members on the car, both members on the car body being formed with cams to engage and move said bolt when the door is closed. 75

13. The combination with a railway car having a door opening and a pair of sliding outside doors to close the same, of a pair of stop and retaining members at the top and bottom on the forward edge of one of said doors, a pair of stop and retaining members on the car within the door opening, locking bolt sockets on the members upon the door, and a locking bolt passing through 80 said sockets and adapted to engage the members on the car, one of the members on the car being formed with a cam over which said bolt rides when the door is closed. 85

14. The combination with a railway car 90 having a door opening and a pair of sliding outside doors to close the same, of a pair of stop and retaining members at the top and bottom on the forward edge of one of said doors, a pair of stop and retaining members 95 on the car within the door opening, locking bolt sockets on the members upon the door, and a locking bolt passing through said sockets and adapted to engage the members on the car, both members on the car body being formed with cams to engage and move 100 said bolt when the door is closed. 105

15. The combination with a railway car having a door opening and a pair of sliding outside doors to close the same, of a pair of stop and retaining members at the top and bottom on the forward edge of one of said doors, a pair of stop and retaining members on the car within the door opening, coengaging vertical, oblique guiding surfaces on 110 said members, locking bolt sockets on the members upon the door, a locking bolt passing through said sockets and adapted to engage the members on the car, one of the members on the car being formed with a cam over which said bolt rides when the door is closed, an intermediate guide for the locking bolt, and a stop on the bolt to bear against the guide so as to keep the bolt from dragging. 115

16. The combination with a railway car having a door opening and a pair of sliding outside doors to close the same, of a pair of stop and retaining members at the top and bottom on the forward edge of one of said doors, a pair of stop and retaining members on the car within the door opening, a locking bolt socket in one of the members on the door, a cam surface on the cooperating fixed member adapted to automatically effect the 120 125 130

movement of the locking element to its locking position; and pockets for a readily removable coopering strip formed on the members on the door.

- 5 17. In combination with a railway car having a door opening and a pair of sliding doors to close the same, a stop and retaining member at the bottom of the door opening intermediate the sides thereof, formed along one side with a vertical, oblique wedging surface and on the top with an inclined cam surface, a member on the bottom of one of the doors at the forward edge formed with a depending, vertical, oblique lip to engage with the wedging surface on the other member and with a socket, and a locking bolt extending through said socket adapted to ride over said cam surface and drop on the other side of the member fixed to the car body 20 when the door is closed.

18. In combination with a railway car having a door opening and a pair of sliding doors to close the same, a stop and retaining member on the car body at the top of the door opening, intermediate the sides thereof, formed with a depending vertical, oblique lip and on the top with an inclined cam surface, a member at the top of the forward edge of the door having a vertical, oblique web to engage the aforesaid lip and with a socket, and a locking bolt extending through said socket having a horizontal portion adapted to ride over said cam surface and drop on the other side of the member on the car body when the door is closed.

19. In combination with a railway car having a door opening and a pair of sliding doors to close the same, a stop and retaining member at the bottom of the door opening intermediate the sides thereof, formed along one side with a vertical, oblique wedging surface and on the top with an inclined cam surface, the member at the bottom of one of the doors at the forward edge formed with a vertical, oblique lip to engage with the wedging surface on the other member and with a socket, a stop and retaining member on the car body at the top of the door opening formed with a depending vertical, oblique lip and on the top with an inclined cam surface, a member on the top of the forward edge of the door having a vertical, oblique web to engage the aforesaid lip and formed also with a socket, and a locking bolt extending through said sockets having a horizontal portion adapted to ride over said last named cam surface to a locking position, the lower end of said bolt adapted to ride over the first named cam surface to a locking position, and an intermediate guide for the locking bolt, the latter being provided with a stop to engage said guide, for the purpose described.

20. In combination with a railway car having a door opening and a pair of sliding doors to close the same, a stop and retaining member at the bottom of the door opening intermediate the sides thereof, formed along

one side with a vertical, oblique wedging surface and on the top with an inclined cam surface, the member at the bottom of one of the doors at the forward edge formed with a vertical, oblique lip to engage with the wedging surface on the other member and with a socket, a stop and retaining member on the car body at the top of the door opening formed with a depending vertical, oblique lip and on the top with an inclined cam surface, a member on the top of the forward edge of the door having a vertical, oblique web to engage the aforesaid lip and formed also with a socket, a locking bolt extending through said sockets having a horizontal portion adapted to ride over said last named cam surface to a locking position, the lower end of said bolt adapted to ride over the first named cam surface to a locking position, and pockets for a coopering strip formed on the members on the door.

21. In combination with a railway car having a door opening and a pair of sliding doors to close the same, a stop and retaining member at the bottom of the door opening intermediate the sides thereof, formed along one side with a vertical, oblique wedging surface and on the top with an inclined cam surface, the member at the bottom of one of the doors at the forward edge formed with a vertical, oblique lip to engage with the wedging surface on the other member and with a socket, a stop and retaining member on the car body at the top of the door opening formed with a depending vertical, oblique lip and on the top with an inclined cam surface, a member on the top of the forward edge of the door having a vertical, oblique web to engage the aforesaid lip and formed also with a socket, a locking bolt extending through said sockets having a horizontal portion adapted to ride over said last named cam surface to a locking position, the lower end of said bolt adapted to ride over the first named cam surface to a locking position, and an intermediate guide for the locking bolt, the latter being provided with a stop to engage said guide, for the purpose described.

22. In combination with a railway car having a door opening, a pair of sliding doors to close said opening, a vertically slideable locking element at the forward edge of one of said doors, means on the car at the upper and lower sides of the door opening with which the extremities of the locking element are adapted to have a locking engagement, and means for automatically moving said locking element to such locking engagement when the door is closed.

23. In combination with a railway car having a door opening, a pair of sliding doors to close said opening, a vertically slideable locking element at the forward edge of one of said doors, means on the car at

the upper and lower sides of the door opening with which the extremities of the locking element are adapted to have a locking engagement, and cams with which the upper 5 and lower ends of said locking element engage to move said element to its locking position when the door is closed.

24. In combination with a railway car having a door opening, a pair of sliding 10 doors to close said opening, a metal reinforcing element fitted over the forward edge of one of said doors, stop and retaining members on the car at the top and bottom of the door opening, intermediate the sides 15 thereof, and cooperating members on the door which are fastened to said metal reinforcing strip.

25. In combination with a railway car having a door opening, a pair of sliding 20 doors to close said opening, a channel-shaped reinforcing strip which extends around the forward edge of one of said doors, stop and retaining members on the car at the top and bottom of the door opening, intermediate the sides thereof, and cooperating members on the door which are fastened to said metal reinforcing strip.

26. In combination with a railway car having a door opening, a pair of sliding

doors to close said opening, a channel-shaped reinforcing strip which extends around the forward edge of one of said doors, stop and retaining members on the car at the top and bottom of the door opening, intermediate the sides thereof, cooperating 35 members on the door which are fastened to said metal reinforcing strip, and automatically operating locking means for holding said door in closed position.

27. In combination with a railway car 40 having a door opening, a pair of sliding doors, a channel-shaped reinforcing strip extending around the forward edge of one of the doors, and a Z-bar on the forward edge of the other door having a flange which 45 projects back of the forward edge of the other door.

28. In combination with a railway car having a door opening, a pair of sliding doors, a channel-shaped reinforcing strip 50 extending around the forward edge of one of the doors, and a Z-bar on the forward edge of the other door having a flange which projects back of the forward edge of the other door, the inner web of said channel 55 bar being offset to provide a recess for the projecting web of the Z-bar.

GARTH G. GILPIN.
